(57) **CLAIM**

The ornamental design for a combined stamp and cap, as shown and described.

DESCRIPTION

FIG. 1 is a front perspective view of a combined stamp and cap showing my new design;

FIG. 2 is a front elevation thereof;

FIG. 3 is a rear elevation thereof;

FIG. 4 is a right side elevation thereof;

FIG. 5 is a left side elevation thereof;

FIG. 6 is a top plan view thereof;

FIG. 7 is a bottom plan view thereof;

FIG. 8 is a cross-section thereof taken along line 8—8 in FIG. 6;

FIG. 9 is a cross-section thereof taken along line 9—9 in FIG. 6;

FIG. 10 is a front elevation thereof of the body of the design with the cap removed;

FIG. 11 is a front elevation thereof;

FIG. 12 is a right side elevation thereof;

FIG. 13 is a left side elevation thereof;

FIG. 14 is a top plan view thereof;

FIG. 15 is a bottom plan view thereof;

FIG. 16 is a front elevation of the cap member;

FIG. 17 is a rear elevation thereof;

FIG. 18 is a right side elevation thereof;

FIG. 19 is a left side elevation thereof;

FIG. 20 is a top plan view thereof; and,

FIG. 21 is a bottom plan view thereof.
